CLAIM

The ornamental design for a “portion of a face of a solar cell module”, as shown and described.

DESCRIPTION

FIG. 1 is a plan view of a portion of a face of a solar cell module, partially shown for ease of illustration, showing my new design; and,

FIGS. 2 and 3 are cross-sectional views thereof taken generally about on lines 2—2 and 3—3, respectively, in FIG. 1.

The dashed lines surrounding all or a portion of the design in the drawing figures represent imaginary boundaries and form no part of the claimed design.
